MULTIPLE DELIVERY LIQUID PUMP

Ludwig le Bret, Berlin-Charlottenburg, and
 Günther Schneeggenburger, Berlin-Halensee,
 Germany

Application-July 3, 1930. Serial No. 465,562

12 Claims. (Cl. 103—2)

This invention relates to a pump for supplying fuel, oils, lubricants, water injection to a plurality of consumption places, as described and shown in the U. S. A. Patent No. 1,568,170, in which it is a question of accurately measuring the quantities of liquid for each individual point of use by only one single operating piston.

The fundamental feature of the invention is that the reciprocating piston movement is obtained by means of only two stroke pins sliding on helical or similarly shaped guide faces, one of which pins owing to its semi-circular cross-section does not touch the induction cam race, whereas both simultaneously bear against the compression cam race. The stroke pins are arranged on the guide piston which is rotatably and shiftably guided vertically in a cylindrical bore. The working piston is suspended for this purpose in a T-groove of the guide piston, which groove is situated on the side directed towards the control valve. By this means only axially directed forces are exerted on the operating piston owing to the articulated connection with the guide piston. A wedge-shaped clutch claw transmits, through a clutch projection on the control valve, the turning movement of the control valve and of the operating piston suspended thereon to the guide piston. The vertical symmetry plane passing through the axis of the stroke pin and through the front of the clutch claw coincides with or forms an extension of the vertical plane through the central axis of the guide piston. The symmetry planes of the clutch projection and of the control channel of the control piston coincides.

The invention is further characterized in that the stroke pin moves always the same distance in advance of the control channel with left hand drive as well as at right hand drive, so that always the same suction segment effects the suction for each exhaust irrespective of the direction of rotation. Moreover, the control valve has only one control channel, which connects the cylinder space alternately with the induction and compression ports of the control sleeve. A further feature consists in that a circulation channel adapted to communicate with the control channel establishes together with a circulation channel in the control sleeve the connection between the control channel and the induction ports.

Constructions are known in single piston pumps, in which two stroke pins are employed for effecting the piston stroke. However in the known construction a rotary cam with only two cam races is employed, which during its rotation effects the induction stroke of the operating

piston through the intermediary of a nonrotatable ring shiftable in the direction of the stroke and connecting the cam positively but not rigidly to the piston by means of stroke rollers, the compression stroke being effected by a piston spring and not by cam parts sliding on one another. A rotating disc control valve with only one control channel is employed and the guide piston is connected to the operating piston by a ball-like connection.

Constructions are also known of single piston pumps with a plurality of points of consumption, distribution being effected by a rotating barrel with a single control channel. The reciprocation of the parts is effected by means of a lever pivoted to the head of the barrel, one end of the lever sliding in a cam groove and the other engaging the plunger. As distinguished from this arrangement a stroke pin moving parallel to its axis is employed according to the invention instead of a lever.

The features of the present invention represent considerable improvements as compared with the construction hitherto known, which improvements are directed chiefly to simple manufacturing and to the suitability of the pump for higher pressures.

In the rigid connection of the operating piston with the stroke disc, according to U. S. A. Patent 1,568,170, it was necessary for the cylinder bore of the pump to register most accurately with the compression curve for a thousandth of a millimeter, as otherwise a simultaneous bearing of the stroke pins on the compression cam race would not be ensured. In order to allow for these inaccuracies, which might occur in the manufacture, a number of stroke pins, corresponding to that of the curve race segments, were provided on the stroke disc of the piston. By this means at least three of the six stroke pins were at the same time in contact with the compression cam race, and consequently not too great bending stresses were exerted on the operating piston. This however only represented a provisional solution, which was not sufficient for high pump pressures, such as are required to-day.

For overcoming these objections the stroke pins have, according to the invention, been separated from the operating piston and are only oscillatably connected together, in order to relieve the operating piston from any bending stress in the event of one sided bearing of the stroke pins. It is thus possible to use a smaller number of stroke pins. The stroke pins are rigidly mounted

in a separate guide piston, which in turn is guided in a cylindrical guide. The operating piston is hingedly connected with the guide piston in such a manner that it is axially movable with 5 out play, whereas it is laterally movable in all directions towards the side of and at an angle to the axial direction. Consequently only forces acting in axial direction can exert themselves on the operating pistons and, as bending forces no 10 longer act on this piston, pistons can be used which are of very small diameter.

The coupling of the guide piston with the rotary driving control valve is effected by two clutch projections on these elements. The clutch is 15 further so constructed that, at right hand or left hand driving of the control slide, the same induction element always effects the induction stroke for supplying the discharge situated thereunder. The coupling of these two parts is 20 therefore so constructed that the solid stroke pin effecting the induction stroke always moves a small angle in advance of the control channel in the control valve, in order to fulfill the above mentioned condition. Consequently these clutch 25 projections, according to the invention, are made wedge-shaped, as this shape offers the greatest material cross section for the small angles of oscillation available. Moreover, this wedge-shaped form of the clutch projections causes a 30 reaction on the control valve through the clutch forces which arise. This reaction causes the control channel of the control valve and its immediate surroundings situated under the clutch projection to bear fully against the control sleeve so 35 that a packing pressure is produced preventing losses due to leakage during the compression stroke. Consequently, a better volumetric degree of efficiency is obtainable with higher pump pressures.

40 In order to further improve the volumetric degree of efficiency, the pump control has also been considerably improved. The number of control channels has been reduced from two to only one and consequently the noxious cylinder space has 45 been considerably reduced. This is important for obtaining a better induction effect with viscous driving media. The control channel connects, during the compression stroke, the cylinder space directly with the actual compression port in the 50 control sleeve, whereas during the induction period two circulation channels, one in the control valve and the other in the control sleeve, serve as connection between the control channel and the actual induction port in the control 55 sleeve. By means of these circulation channels the registering portions between control channel and the induction ports in the control valve during the compression stroke are triplicated. The 60 diameter of the control valve remains the same, as the pressure liquid must pass from the control channel to the circulation channel in the control sleeve, from this into the circulation channel in the control valve, and thence to the 65 induction port in the control sleeve. Without these two circulation channels only one registering position would have to be passed by the pressure liquid from the control channel to the induction port, which would then be situated in 70 the plane of the pressure ports, instead of the circulation channel in the control sleeve—that is only one third of the covering path. As these compressing losses are decisive for the pump pressures, pump pressures approximately three 75 times as great are obtained by this feature of

the invention with the same volumetric degree of efficiency.

An embodiment of the invention is illustrated by way of example in the accompanying drawings in which:

Fig. 1 is a cross section through the pump.

Fig. 2 is a vertical section of Fig. 1.

Fig. 3 shows a section on line III—III of Fig. 1.

Fig. 4 shows a section on line IV—IV of Fig. 1.

Fig. 5 is a diagrammatic view of the control, the cam groove and the inner casing surface of the control sleeve being shown in development.

In the casing 23 the control valve 3 rotates always at the same angle α between stroke pins 6' in advance of the direction of movement independently of the direction of rotation through the intermediary of the worm gear 1, 2. In the axis of the valve, a cylinder 25 is provided with operating piston or compressor 4, which is oscillatably suspended by means of a T-groove 24 in the guide piston 5 situated thereover.

The control valve 3 has a catch 10 on its upper end, which bears against a wedge-shaped nose 9 on the lower part of the guide piston 5 in such a manner that, on the rotation of the control valve 3, the guide piston 5 is also rotated. A stroke bolt 6 is mounted in a bore perpendicular to the axis of rotation in the guide piston 5, the ends 6', 6² of which bolt project laterally from the guide piston. The end of stroke pin 6² is a half pin. These two stroke pins 6' and 6² extend into a cam groove formed by cut out portions in the upper compression curve 7 and by a plurality of independently movable suction cam segments 8, arranged under the upper compression curve 7 and adjustable by means of a spindle 21 and set nut 22. The control valve 3 is surrounded by a stationary control sleeve 13 having bores for the control corresponding in their arrangement exactly to the rising and falling curves of the cam groove. An induction line 19 and discharges 14 leading to the corresponding points of lubrication are arranged in the casing 23.

Fig. 5 shows the effect of the advance movement of the stroke pin 6' relative to the control channel 11 on the independency of the direction of rotation in order that the same induction segment 8 shall effect the induction stroke for supplying the pressure port 12. This figure also shows the effect of the circulating channels 15, 16 on the packing covering between the suction port 17 and the pressure port 12 in the control sleeve 13.

The upper part of Fig. 5 shows the development of the curve 7 and segments 8 with the stroke pins 6' in various positions therein. The lower part of this figure shows the development of the control sleeve 13 and the control channel 11 and the circulating channel 16 (shown in dotted lines) arranged in the control valve 3, also in different positions. The independency of the stroke pins 6', the control channel 11, and circulating channel 16 are shown at the beginning of the induction stroke and at the end of the pressure stroke, the left portion of the figure being for turning to the right and the right portion for turning to the left.

Only the complete stroke pin 6' is shown as it slides through the curve 7 as this effects both the induction and the pressure stroke and is responsible for the control. The half stroke pin 6² only bears on the race of the pressure curve and then always together with the stroke pin 6' but always on the opposite side of the pressure

curve arranged in a circle. The path of the stroke pin 6' is indicated for both directions of rotation.

During the turning to the right (left portion 5 of the figure) the control channel 11 in the control valve 3 sucks from the suction port 17 situated on the left under the suction segment, whereas the stroke pin 6' effects the induction stroke of the operating piston 4 by sliding upwards on the left curve race of the suction segment 8. The stroke pin 6' as shown moves a certain distance in advance of the control channel 11. During the downward movement of the stroke pin 6', that is during the pressure stroke, 10 the control channel 11 comes to register with the pressure port 12 situated under the controlling suction segment 8.

During the turning to the left (right portion 20 of the figure), the stroke pin 6' again moves in advance of the control channel 11 but in this instance towards the left. During this direction of rotation the suction is effected from the suction port 17 situated on the right under the controlling suction segment 8 during the upward 25 movement of the stroke pin on the right side of the curve of the suction segment 8. During the downward movement of the stroke pin 6' during the pressure stroke the control channel 11 again comes into register with the pressure port 12 situated under the controlling suction segment 8.

In the curve groove shown at the top the parts 35 of the curve effecting the induction and pressure strokes are indicated by cross-hatching. During the rotation to the right the left curve of the suction segment 8 effects the suction stroke by the upward movement of the stroke pin 6', whereas the right portion of the pressure curve 7 effects the pressure stroke by the downward movement of the stroke pin 6'.

40 During the rotation to the left the opposite sides of the curves to those marked by cross-hatching effect the induction and pressure strokes.

In Fig. 5 on the right at the top an entirely 45 lowered suction segment 8 is shown in dotted lines. The stroke pin 6' in this position slides over the suction segment without being raised and consequently without imparting a suction stroke to the operating piston 4. Consequently 50 at this point no pressure stroke will occur and no feed medium supplied to the pressure port under this suction segment.

The circulating channel 15 in the control sleeve 13 and the circulating channel 16 in the rotary control valve 3 establish communication between 55 the suction port 17 and the control channel 11 during the induction period. The control channel 11 is arranged on a different plane to the suction port 17 in the control sleeve. During the 60 induction stroke the conveying medium is supplied by the suction underpressure occurring in the cylinder from the suction port 17 to the control channel 11 through the registering circulating channels 16, 15. During the pressure 65 stroke however the medium is supplied from the control channel 11 directly to the pressure port 12 of the control sleeve.

In the right portion of Fig. 5 is shown diagrammatically by means of arrows 1, 2, and 3 the path 70 which a portion of the conveying medium must follow at the end of the pressure stroke, which medium does not come into the pressure line at low degree of efficiency. This lost conveying medium which does not pass into the pressure line must pass from the control channel 11 to the

circulating channel 15 at 1, thence to the circulating channel 16 at 2 and finally from here to the suction port 17 at 3.

The operation is as follows:—

The control valve 3 with the operating piston 4 is rotated by the worm gearing 1, 2. The clutch projection 10 of the control valve bears against the nose 9 of the guide piston 5 and rotates same. The stroke pins 6' and 6² of the stroke bolt 6 of the guide piston 5 engage in cavities of the upper compression cam 7 and run on the rising and descending portions of the cam groove through the rotation of the guide piston 5 so that the guide piston 5 and operating piston 4 are moved up and down. The upward movement of the piston 4 constitutes the induction stroke and the downward movement the compression stroke.

80 During the downward movement, that is during the compression stroke, the cylinder space 25 is connected with the outlet 14, leading to the corresponding lubricating point, by means of a control channel 11 of the control valve 3 and a corresponding pressure port 12 of the control sleeve 13 (Fig. 1).

85 During the upward movement, that is at the suction stroke of the piston 4, the cylinder space 25 is connected by means of a control channel 11 of the control valve 3 and a circulating channel 15 of the control sleeve 13 by means of a circulation channel 16 in the control valve 3 with a suction port 17 of the control sleeve, which is connected by a collecting groove 20 with the suction pipe 19 (Fig. 2). The bores of the control sleeve 13 for the control are arranged according to the rising and falling curves of the cam groove. The piston 4 therefore always sucks from the common induction pipe 19, but delivers the sucked in liquid consecutively to the outlets 14 of the casting 23. The solid stroke pin 6' of the stroke bolt 6 controls alone the induction stroke, as the other stroke pin 6², constructed as a half pin is always situated above the suction elements 8 without however touching these. If a suction segment 8 is for example lowered by the adjusting device 110 21, 22, a shorter induction stroke of the piston 4 120 is obtained at this point so that the corresponding outlet 14 will receive less liquid. Consequently each individual outlet can be adjusted as regards the quantity supplied between zero and maximum independently of the others.

125

We claim:—

1. In a pump for delivering liquid to a plurality of consumption places the combination of an operating piston, a control valve surrounding and adapted to rotate with said operating piston, 130 stroke pins above said control valve, means for connecting said pins to said operating piston, and means for effecting the reciprocating motion of said operating piston and the induction and compression stroke of said operating piston through 135 the intermediary of said stroke pins.

2. In a pump for delivering liquid to a plurality of consumption places, the combination of an operating piston, a control valve surrounding and adapted to rotate with said operating piston, 140 two stroke pins of different cross sectional areas above said piston, a cam drive having suction cam races, with which only the pin of larger cross sectional area engages, and compression cam races with which both of said pins engage. 145

3. In a pump for delivering liquid to a plurality of consumption places the combination of an operating piston, a control valve surrounding and adapted to rotate with said operating piston and having a control channel, stroke pins above 150

- said control valve one of said pins of larger cross sectional area than the other, means for connecting said pins to said operating piston, a casing surrounding said control valve having a plurality of outlets leading to the different consumption places, a cam drive adapted to effect the reciprocating motion of said piston and the induction and compression stroke of said operating piston through the intermediary of said stroke pins, and induction segments on said cam drive adapted to coact with the stroke pin of larger cross sectional area moving at a like angle in advance of said control channel to cause said induction stroke for its co-ordinate outlet irrespective of the direction of rotation.
4. A pump for delivering liquid to a plurality of consumption places, comprising in combination an operating piston, a control valve surrounding and adapted to rotate with said operating piston, stroke pins above said control valve, means for connecting said pins to said operating piston, means for effecting the reciprocating motion of said piston and the induction and compression stroke through the intermediary of said stroke pins, a casing surrounding said control valve having suction and pressure ports, said control valve having only one control channel adapted to connect the space in said casing alternately with the suction and pressure ports of said casing.
5. A pump for delivering liquid to a plurality of consumption places, comprising in combination an operating piston, a control valve surrounding and adapted to rotate with said operating piston, stroke pins above said control valve, means for connecting said pins to said operating piston, means for effecting the reciprocating motion of said piston and the induction and compression stroke through the intermediary of said stroke pins, a casing surrounding said control valve having suction and pressure ports and a circulating channel, said control valve having a control channel and a circulating channel adapted to co-operate with the circulating channel in said casing to establish the connection with the suction ports in said casing.
6. In a pump for delivering liquid to a plurality of consumption places the combination of an operating piston, a control valve surrounding and adapted to rotate with said operating piston, a guide piston above said operating piston, means for transmitting the rotary movement of said valve to said guide piston, stroke pins projecting from said guide piston, and means for effecting the reciprocating motion of said pistons and the induction and compression stroke of said operating piston through the intermediary of said stroke pins.
7. In a pump for delivering liquid to a plurality of consumption places the combination of an operating piston, a control valve surrounding and adapted to rotate with said operating piston, a guide piston above said operating piston, stroke pins projecting from said guide piston, and a casing having a cylindrical bore adapted to rotatably and shiftably guide said guide piston, said stroke pins adapted to guide said operating piston in axial direction.
8. In a pump for delivering liquid to a plurality of consumption places the combination of an operating piston, a control valve surrounding and adapted to rotate with said operating piston, a guide piston above said operating piston, said operating piston hingedly connected and laterally shiftable relative to said guide piston, to allow forces to be exerted on said operating piston only in axial direction, stroke pins projecting from said guide piston, and means for effecting the reciprocating motion of said pistons and the induction and compression stroke of said operating piston through the intermediary of said stroke pins.
9. In a pump for delivering liquid to a plurality of consumption places the combination of an operating piston, a control valve surrounding and adapted to rotate with said operating piston, a guide piston above said operating piston having a T-groove on the side directed towards said control valve adapted to oscillatably support said operating piston, stroke pins projecting from said guide piston, and a casing having a cylindrical bore adapted to rotatably and shiftably guide said guide piston, said stroke pins adapted to guide said operating piston in axial direction.
10. In a pump for delivering liquid to a plurality of consumption places the combination of an operating piston, a control valve surrounding and adapted to rotate with said operating piston, a guide piston above said operating piston, a clutch projection on said valve, a wedge-shaped nose on said guide piston engaging said clutch projection adapted to transmit the rotary movement of said control valve and of said operating piston to said guide piston through the intermediary of said clutch projection, stroke pins projecting from said guide piston, and means for effecting the reciprocating motion of said pistons and the induction and compression stroke of said operating piston through the intermediary of said stroke pins.
11. In a pump for delivering liquid to a plurality of consumption places the combination of an operating piston, a control valve surrounding and adapted to rotate with said operating piston, a clutch on said valve, a guide piston above said operating piston, a nose on said guide piston engaging said clutch projection, a nose on said guide piston engaging said clutch projection adapted to transmit the rotary movement of said valve to said guide piston, stroke pins projecting from said guide piston one of said stroke pins being of larger cross sectional area than the others and situated with said clutch projection in a plane passing through the central axis of said guide piston, and means for effecting the reciprocating motion of said operating piston and the induction and compression stroke of said operating piston through the intermediary of said stroke pins.
12. In a pump for delivering liquid to a plurality of consumption places the combination of an operating piston, a control valve surrounding and adapted to rotate with said operating piston and having a control channel, a clutch projection on said valve, the centre of said control channel lying with said clutch projection in a plane through the central axis of said control valve, a nose on said guide piston engaging said clutch projection adapted to transmit the rotary movement of said valve to said guide piston, stroke pins projecting from said guide piston, and means for effecting the reciprocating motion of said operating piston and the induction and compression stroke of said operating piston through the intermediary of said stroke pins.
